UNITED STATES PATENT OFFICE.

HANS ALBERT PHILIPS, OF STRATFORD, CONNECTICUT, ASSIGNOR TO THE AMERICAN FABRICS COMPANY, A CORPORATION OF CONNECTICUT.

DESIGN FOR LACE.

Application filed April 25, 1923. Serial No. 5,940. Term of patent 14 years.

To all whom it may concern:

Be it known that I, HANS ALBERT PHILIPS, a citizen of the United States, residing at 2070 Main Street, Stratford, county of Fairfield, State of Connecticut, have invented a new, original, and ornamental Design for Lace, of which the following is a specification, reference being had to the accompanying drawing, forming part thereof.

The figure is a plan view of a piece of lace showing my new design.

I claim:

The ornamental design for lace substantially as shown.

H. ALBERT PHILIPS.
